UNITED STATES PATENT OFFICE

2,600,595

HEAT EXCHANGER

John R. Wilson, Penn Township, Allegheny County, Pa., assignor to Hanlon & Wilson Company, Wilkinsburg, Pa., a corporation of Pennsylvania

Application January 13, 1950, Serial No. 138,298

2 Claims. (Cl. 257—246)

1

This invention relates to heat exchangers. Although the invention may be used for other purposes, it is described herein as applied to a heat exchanger in which the hot exhaust gases of an airplane engine are used for heating air, the heated air being employed for preventing icing of the wings of an airplane.

In the accompanying drawings which illustrate a preferred embodiment of the invention:

Figure 1 is a side elevation of the heat exchanger;

Figure 2A and 2B when taken together constitute a vertical longitudinal section through the heat exchanger, taken on the line II—II of Figure 3, these figures being on a larger scale than Figure 1;

Figure 3 is an end elevation taken on the line III—III of Figure 1 but to a larger scale;

Figure 4 is a vertical transverse section taken on the line IV—IV of Figure 1 but on a larger scale; and

Figure 5 is a vertical transverse section taken on the line V—V of Figure 1 but on a larger scale.

Referring more particularly to the accompanying drawings, the heat exchanger comprises a shroud or casing indicated generally by the reference numeral 1 and made up of sections 1a, 1b, 1c and 1d assembled in end to end relationship. A slip joint 2 is provided between the sections 1a and 1b and a welded joint 2a is provided between section 1b and 1c. The shroud is cylindrical in cross-section, as shown in Figures 4 and 5. A core, indicated generally by the reference numeral 3, is located inside of and spaced from the shroud 1 to form an outer passage 4 for air or other fluid to be heated, as hereinafter explained. The shroud 1 is supported on the core 3 by pins 5 which are welded to the core at their inner ends and which slidably support the shroud at their outer ends. These pins are grouped in circles which are spaced longitudinally of the core.

An inner tube indicated generally by the reference numeral 6 is located inside of and spaced from the core 3. It is made up of sections 6a and 6b having a slip joint 7 between these sections. The inner tube 6 is supported from the core 3 by tubes 8 which are welded at their inner ends to the inner tube 6 and at their outer ends are welded to feet 9 which float against wear pads on the core 3. In the illustrated embodiment of the invention the tubes 8 are used in groups of three tubes, the groups being spaced longitudinally of the heat exchanger.

Longitudinally extending walls 10 divide the 55 providing good heat transfer between the core

2

outer passage 4 formed by the shroud 1 and the core 3 into a plurality of longitudinally extending outer passages 11, 12, 13, 14, 15 and 16, as shown in Figure 4. Each of the passages 11, 13 and 15 is blocked off intermediate its ends by a transversely extending wall 17, as shown in Figure 2A. Three conduits 18 are connected at their inner ends 19 to the forward end of the inner tube 6. The outer end 20 of each conduit is connected to the core 3 by a weld designated by the reference numeral 21, the weld being located on the outside surface of the core 3 so that the weld is located in the outer passage 4.

Air to be heated enters an air inlet 23 and flows through a curved passage 24 into the heat exchanger. The inlet faces forwardly of the airplane so that when the plane is in motion the inlet and passageway 24 act as a scoop to force air under pressure through the heat exchanger. The air passes upwardly from the passageway 24 into an annular chamber 25. A portion of the air passes from the chamber 25 through the outer passages 12, 14 and 16 which extend substantially the whole length of the heat exchanger. It then passes into an annular chamber 26 located at the rear end of the heat exchanger and from the chamber 26 flows into an outlet conduit 27.

Another portion of the air in the chamber 25 flows into the passageways 11, 13 and 15 and from there flows through the conduits 18 into and through the inner tube 6. This portion then flows through a conduit 28 into the outlet conduit 27.

The hot engine exhaust gases or other heating fluid enters the forward end 29 of the core 3 and then flows through the space between the core and the inner tube 6 and leaves the heat exchanger at the end 30 of the core. In the drawings the flow of air or other fluid to be heated is designated by the double tailed arrows and the flow of exhaust gases or other heating fluid is designated by the single tailed arrows.

It will be seen that in my heat exchanger fluid to be heated flows through outer passages 12, 14 and 16, and also through an inner passage formed by the inner tube 6, while the heating fluid flows through an intermediate passage which is located between the inner tube 6 and the core 3. Thus the heating fluid is surrounded on both its outside and its inside with fluid to be heated and this arrangement provides very effective heat transfer. The inner tube 6 also causes the heating fluid to be forced against the core 3, thereby

and the air flowing through the outer passages 12, 14 and 16.

The invention is not limited to the preferred embodiment but may be otherwise embodied or practiced within the scope of the following claims.

I claim:

1. A heat exchanger comprising a shroud, a hollow core located inside and spaced from said shroud to form an outer passage between said shroud and core and having an inlet and an outlet, an inner tube located inside and spaced from said core throughout its length and having an inlet and an outlet, conduits connecting said outer passage and said inner tube, said conduits being welded to said core with the welds located in said outer passage, means for flowing a first portion of the fluid to be heated through a part of said outer passage adjacent said welds and then through said conduits and then through said inner tube, means for flowing a second portion of the fluid to be heated through another part of said outer passage which is spaced circumferentially from the part of said outer passage through which said first portion flows, and means for flowing heating fluid through the space between said inner tube and said core.

2. A heat exchanger comprising a shroud, a hollow core located inside and spaced from said shroud to form an outer passage having an inlet and an outlet, longitudinally extending walls dividing the space between said shroud and core

into a plurality of separate longitudinally extending outer passages, some of said outer passages being blocked off intermediate their ends and others being open between their ends, an inner tube located inside and spaced from said core and having an inlet and an outlet, conduits connecting said inner tube with those outer passages which are blocked off, means for flowing a portion of the fluid to be heated through the forward parts of said blocked off outer passages and then through said conduits and then through said inner tube, means for flowing another portion of the fluid to be heated through said outer open passages, and means for flowing heating fluid through the space between said inner tube and said core.

JOHN R. WILSON.
